His attorney.

UNITED STATES PATENT OFFICE.

GEORGE F. KALER, OF ROCKLAND, MAINE.

LIFTING-JACK.

SPECIFICATION forming part of Letters Patent No. 352,650, dated November 16, 1886.

Application filed August 12, 1886. Serial No. 210,717. (No model.)

To all whom it may concern:

Be it known that I, GEORGE F. KALER, residing at Rockland, in the county of Knox and State of Maine, have invented certain new and useful Improvements in Carriage-Jacks, of which the following is a specification, reference being had therein to the accompanying drawings.

This invention relates to lifting-jacks for carriages or wagons; and it consists in the carriage-jack constructed substantially as herein-after described and claimed, by which the entire body of a carriage may be lifted at once, so that any or all of the wheels may be readily removed or replaced.

In the drawings, Figure 1 is a perspective view of my carriage-lifting jack. Fig. 2 is a side elevation showing the depressed position in dotted lines.

20 The letters A A indicate the base-pieces or stringers which form the foundation of this jack. The stringers are held together by the ties B B, and preferably have small trucks at their front ends.

25 At one end of the jack two braces, C C, are pivoted to the stringers A A, and the upper ends of these braces are pivoted to the top bars, D D. The bars D D are substantially counterparts of the stringers A A, and are held parallel to each other by the ties E E.

At or near the other end of the jack from the braces C pairs of links F F are pivoted to the top bars, D D. The lower ends of these links are pivoted to the bent levers G G at f 35 f, a short distance above the points g g, where these bent levers G G are pivoted to the stringers A A. The levers G G terminate at their outer ends in handles H H. Thus the links F F and the parts of levers between the lower 40 ends of said links and the pivots g g form toggle-levers between the stringers A A and the top bars, D D. The rigid draw-bars I I connect the pivots f f of these toggle-levers with the upper ends of braces C, to which these draw 45 (or push) bars are pivoted. Thus the upper end of the braces C will partake of the movement of the joint of the toggle-lever, and will thus, when swinging, lift the top bars.

When the jack is lowered, as in Fig. 1, the whole device can be passed under the running-gear of the carriage or wagon of ordinary height. Then by lifting on the handles H H of levers G G the toggle-joint is straightened, and at the same time the brace C is swung into nearly a vertical position, thus lifting 55 both ends of the top bars. The levers G finally bear against the ends K of the bars D at the time the toggle-joint has been carried to a position a little past the perpendicular. This contact of the levers with the top bars holds 60 the jack firmly in elevated position, no other locking device being necessary.

To lower the carriage-body or other weight which has been lifted, it is only necessary to swing back the levers G G.

65 This device, by reason of the compound leverage afforded, is very powerful, and can be quickly brought into position for lifting a carriage-body or other similar weight.

It is apparent that one-half of the device, as 70 shown in Fig. 2, will be operative for use in certain positions.

I claim—

1. The combination of the stringers and the top bar, the pivoted brace, as C, connecting 75 the same at one end, the toggle-lever forming the other end connection, and a rigid bar connecting the toggle lever with the brace, so that the top bar will be lifted by the movement of the toggle-levers, substantially as described.

2. The combination, with the stringers A A and top bars, B B, tied in pairs, as described, of the braces C C, and the toggle-levers pivotally connected to said stringers and bars, the handles H forming extensions of the lower 85 members of the toggle-levers, said handles moving in line with the top bars, and the draw-bars I connecting the pivot of the toggle-levers with the pivoted braces, all substantially as described.

In testimony whereof I affix my signature in presence of two witnesses.

GEORGE F. KALER.
